Hugh P. Rankin
By his Atty,
R. D. Smith

UNITED STATES PATENT OFFICE.

HUGH P. RANKIN, OF ALLEGHENY CITY, PENNSYLVANIA.

MEAT-CHOPPER.

SPECIFICATION forming part of Reissued Letters Patent No. 9,182, dated April 27, 1880.

Original No. 140,950, dated July 15, 1873. Application for reissue filed February 5, 1879.

To all whom it may concern:

Be it known that I, HUGH P. RANKIN, of Allegheny, in the county of Allegheny and State of Pennsylvania, have invented a new and useful Improvement applicable to Meat-Choppers; and I do hereby declare the following to be a full, clear, and exact description of the same, reference being had to the accompanying drawings, forming part of this specification.

The invention consists in the crank-movement mounted in a frame capable of yielding when the crank-rods are arrested by some refractory substance to prevent disaster to the machine.

The revolving table and the cutters which constitute the characteristics of a meat-chopper are not new.

Figure 1 is a front elevation, partly broken out. Fig. 2 is a plan view. Fig. 3 is a detail view of slide.

In the drawings, A A represent the uprights of the frame, having vertical slots a a opening out at the top, and B is the bottom or bed plate which supports the table D.

Heretofore, in reciprocating machines of this character, there has been no adequate compensation for the untimely arrest of the crank-rod by reason of the resistance of some unusually refractory substance. To avoid the disastrous consequences which sometimes attend such arrests, I mount my driving crank-shaft K in bearings capable of sliding upward or yielding, so as to permit the revolution to continue when the crank-rod is arrested, as set forth.

To this end, H is a frame fitted to slide in the grooves a a in the upright frame A, and the boxes or bearings for the crank-shaft K are mounted on said frame, so as to move up and down with the same.

The crank-shaft K is provided with the cranks k k, and the slides L mounted thereon and moving in the yokes G as intermediates between said cranks and the crank-rods g g', which are operated by said cranks. The slides L are mounted in yokes G G, to the upper and lower sides whereof the crank-rods g g' are attached respectively. As the cranks k revolve the slides L move back and forth in said yokes, and the rods are moved up and down in guides

h in the frame H. The frame H, carrying the crank-shaft K, is retained at the bottom of its guide a a, or against the screws J, by gravity; and hence, if one or more of the crank-rods are suddenly arrested in their reciprocations the revolution of the crank-shaft will not be arrested, because the frame carrying the shaft will rise up far enough to permit the shaft to pass the lower dead-point, and thus damage to the machine will be avoided.

Set-screws J under the crank-shaft bearings of the frame H serve to adjust the said shaft, as shown.

In the drawings my invention is represented as applied to a meat-chopper, and D is a rotating table, which is made in the usual manner of blocks of wood, with the grain in line with the line of movement of the chopping-knives E, which are arranged in pairs on heads attached to the lower ends of the crank-rods g'. These knives are slotted at e, so that their adjustment may be changed from time to time, as may be required. The knives are secured to their heads by screws f.

The table D is shown as revolving in a socket-bearing in the block C, and it is actuated by a pinion at the end of shaft of the pulley P, which receives motion from the crank-shaft K by means of the elastic or extensible belt R.

I claim—

1. The combination of a bodily-movable frame H and the crank-shaft K mounted thereon with the reciprocating rod or rods g g', connected with and operated by said cranks, substantially as and for the purposes set forth.

2. The combination of a bodily-movable frame H and crank-shaft K mounted thereon with the reciprocating rods g g', connected with and operated by said cranks, and the rotating table to support the material under treatment, substantially as described, and for the purpose specified.

3. The combination of a bodily-movable crank-shaft, K, connected with and operating the reciprocating rod or rods g g', with the rotating table D and the extensible driving-connection R, to transmit motion to said table, substantially as set forth.

4. The bodily-moving frame H, moving in guides a a, and the crank-shaft K, connected

with and operating the rod or rods $g\ g'$, in combination with the adjusting-screws J, substantially as described, and for the purpose set forth.

- 5 5. A bodily-movable frame, H, bearing the crank-shaft K, rod or rods $g\ g'$, connected with and operating by said crank, combined with the knives E and table D, substantially as and for the purpose specified.
- 10 6. The combination of a bodily-movable

frame, H, bearing the shaft K, rod or rods $g\ g'$, yoke G, knives E, rotary table D, and extensible belt, R, substantially as described, and for the purpose specified.

In testimony that I claim the foregoing as 15 my invention I affix my signature in presence of two witnesses.
